UNITED STATES PATENT OFFICE.

CLARENCE P. HOLLISTER, OF NEW YORK, N. Y.

LUBRICATION OF INTERNAL-COMBUSTION ENGINES.

1,414,644.

Specification of Letters Patent.

Patented May 2, 1922.

Application filed February 28, 1918. Serial No. 219,623.

To all whom it may concern:

Be it known that I, CLARENCE P. HOLLISTER, a citizen of the United States, residing at New York, in the county of New York and State of New York, have invented certain new and useful Improvements in the Lubrication of Internal-Combustion Engines, of which the following is a specification.

10 This invention relates to a lubricating system for internal combustion engines and is particularly applicable to engines having rotary sleeve valves.

It is quite important that the contact surface between the rotary valve and the cylinder should be constantly lubricated, especially as these parts are subjected to the intense heat from the exploding gases. It has been proposed to introduce lubricating oil with the explosive charge by mixing oil with the fuel supply. This has not been successful, however, for various reasons, among others because the lubricating oil will not be properly atomized by the carbureting apparatus and even when sprayed into the manifold, it will not combine with the carbureted fuel charge to form a combustible mixture and is therefore, detrimental.

30 One purpose of my invention is to introduce a lubricant into the air supply of the carbureter in such a finely divided state and at such a temperature that it forms a homogeneous mixture, and remains in a vaporous state, so that it is entirely consumed with the fuel charge. I have found that the lubricant should be introduced in an exceedingly fine state, like an oily mist, and that it can only form a homogeneous mixture when it is introduced into the carbureting apparatus. Moreover it must be at a sufficiently high temperature to prevent condensation and separation in order to maintain the homogeneity of the fuel mixture.

45 However the temperature must not be too high as this reduces the efficiency due to the expansion of the gaseous mixture resulting from the explosion.

The oil in the crank-case is constantly maintained in a state of violent agitation by the motion of the engine cranks, causing the upper portion of the case to be constantly filled with an exceedingly fine oily spray or mist which is in just the proper state for my system of lubrication. Accordingly I introduce this oily mist or spray into a chan-

nel or passage which conveys heated air to the carbureter. My invention will be understood from the following description in connection with the accompanying drawings 60 in which—

Figure 1 is a side elevation, partly in section of an internal combustion engine embodying my invention; Fig. 2 is a vertical sectional view on the line 2—2 of Fig. 1; 65 Fig. 3 is a side elevation taken upon the opposite side from Fig. 1; Fig. 4 is a central vertical section on the line 4—4 of Fig. 6; Fig. 5 is a partial front elevation of the engine casing; and Fig. 6, is a partial bottom plan view of the engine casing.

I have illustrated my lubricating system in connection with a four cylinder four cycle engine having rotary sleeve valves. As is well understood, the sleeve valves 5 revolve 75 upon bearing rings 6, supported upon webs or lugs 7 projecting from the engine base casting, and are provided with gears 8, meshing with pinions 9 on the timing shaft 10, the latter being driven from the crank 80 shaft 12, through gears 14, 15, 16.

It will not be necessary to describe in detail the usual parts of engines as these elements will be recognized by engineers. The water circulating pump 20, is connected by 85 pipe 21, connected at 21^a with the water space 23, of the water jacket 24 surrounding the cylinders 25, the pump shaft 27, being geared at 28 with a pinion 29 on the timing shaft 10. The pipe connecting the water jacket with the radiator is indicated at 31. I have indicated at 34 the usual motor starter and generator provided with the well known "Bendix drive" gear connection 90 35, the distributor being indicated at 36. 95

The lubricating oil in the sump or oil pan 40, passes through a sieve or strainer 41, into the chamber of the oil well 42, from which it is pumped through the passage 43 to the oil pump 45, and thence forced into 100 the main oil distributing channel 50, extending longitudinally through the engine cylinder casting; the connection with the supply line from the oil pump being made through the branch 50^a opening through the 105 bottom of the casting. The drive shaft 46 of the oil pump is provided with a pinion 47 which meshes with pinion 9, on the timing shaft. The oil supply channel 50, is connected centrally by a lateral branch 50^b 110 opening through the casting at 50^c, with the bore of the hollow standard 60, which sup-

ports the central bearing 61, of the crank shaft. At the ends of the casing the oil channel 50 terminates in openings 50^a which connect with the hollow standards 62 and 5 63, supporting the end bearings 65, 67, of the crank shaft. In this manner the main bearings of the crank shaft are constantly supplied with oil under pressure. The oil may be distributed from these bearings to 10 the wrist-pin bearings 68 by providing suitable channels through the cranks and also to the interior of each cylinder and to the pitman bearings 69 through channels in the connecting rods 70, this oiling system being 15 well known and requiring no explanation. The oil level in the pan or oil well is shown by the indicator 71.

By reason of the rotation of the cranks of the engine shaft and the rapid reciproca- 20 tion of the connecting rods, the air mixed with finely divided particles of oil is in a state of constant agitation so that the chamber of the crank case is continually filled with an oil mist. I have discovered that this 25 oil-laden air in the crank case will form a homogeneous mixture with the carburetted charge introduced into the engine manifold if it is introduced under proper conditions into the carburetting chamber and that the 30 oily particles are in such a state of subdivision that they are entirely consumed with the charge in the combustion chamber without any deposition. I am therefore, enabled to utilize this oily component of the charge 35 as it impinges upon the outer periphery of the rotary valve during the opening and closing thereof, to deposit a minute film of oil thereon in a most effective manner. As previously stated, the oily component of the 40 charge which passes through the inlet port is consumed with the charge.

I have found that it is desirable to heat the air and introduce the oily mist from the crank case therein before it is led into the 45 carbureter. For this purpose I provide air channels 80, 80' in the casting surrounding the cylinders and adjacent the lower side of the water jacket so that the air will be maintained at about the temperature of the water 50 and not become too hot as would be the case if the air channel were isolated from the water jacket and in contact with cylinder walls. For the same reason I locate the air channel at the end of the cylinder distant 55 from the explosion chamber 81. Screened air inlets 82, enter the channel 80 at several points, preferably at points opposite the juncture of the cylinders. The channels 80 and 80' are connected at the center of the engine by a cross channel 80^a. After becoming heated in passing around the cylinders, the air is conducted through an outlet 83 from the channel 80' into the inlet pipe 84 of the carbureter 85. The inlet is also provided 60 with an adjustable valve 86 which may be

opened more or less to admit additional air directly into the carbureter. In this manner I am able to control the temperature of the resulting mixture.

The oil-laden air or oily mist in the crank 70 case is drawn from the forward end around the gears 15, 16, and passes rearwardly through the timing shaft passage 87 between the bottom wall of the cylinder casting and the top wall of the engine base, as 75 indicated by the arrows in Fig. 1 and is thence carried upward through the openings 88, 89 into the heated air passage 80' and the cross-passage 80^a. The heated air prevents the entering oily mist from condensing 80 and by the time the air passes through the outlet 83 into carbureter inlet 84, the oily particles have become thoroughly disseminated throughout the column of air. As a 85 consequence the carburetted charge which passes from the carburetting chamber 85 into the intake manifold 90, is thoroughly homogeneous and is impregnated with the finely divided oily particles. As this gaseous charge impinges upon the outer surfaces 90 of the revolving sleeve valves the contacting minute particles of oil are deposited thereon and form a thin film which effectually lubricates the upper portions of the valves, while on account of the thorough incorporation with the charge, all of the oily 95 particles entering the combustion chamber 81 are entirely consumed.

The air which is withdrawn from the 100 crank casing is replaced by air entering the "breather" constituted by the screened opening in the cap 91 of the oil inlet filling tube. The temperature of the air in the carbureter inlet may be regulated or controlled by 105 adjusting the valve 86.

The vaporization of the gasoline or fuel is facilitated if it is supplied to the float 110 chamber 94 in a heated condition, but it must not be heated to a high temperature. I have found that a proper degree of heat is imparted by conducting the gasoline supply pipe 95 through a portion of the water jacket as I have indicated in Fig. 6.

My lubricating system and method of incorporating an oily medium in the explosive 115 charge will be understood from the foregoing description. I have overcome the defects of prior attempts to introduce a lubricant with the charge by first obtaining a supply of heated oily spray or mist and then 120 thoroughly incorporating it in a heated column of air which is afterward carburetted to form a homogeneous explosive charge. As a result of this complete admixture of the finely divided oily particles with the charge, these particles are entirely consumed 125 without any deposition, every trace being swept out with the exhaust through the exhaust manifold 92. My method of lubricating those portions of the rotary sleeve 130

valves which are subjected to the blasts of the inlet gases ensures a constant and unfailing supply of lubricating particles, the importance of which will be appreciated by engineers and those familiar with the operation of internal combustion engines.

I have described in detail the particular construction illustrated in the accompanying drawings for the purpose of clearly disclosing an embodiment of my invention, but it will be evident to experts in this art that various changes and modifications can be made within the scope of my claims and without departing from my invention.

15 I claim:—

1. The method of lubricating those portions of rotary sleeve valves of internal combustion engines exposed to the impact of the inlet gases which comprises preheating the air supplied to the carbureter, and impregnating said preheated air with an oil spray or oily mist, conducting the mixture through a channel having a water-jacketed

wall to prevent over-heating, and introducing the resulting homogeneous mixture 25 into the carbureter.

2. A lubricating system for rotary valves of internal combustion engines, comprising an air channel passing adjacent the engine cylinders and adjoining the water jacket 30 thereof and provided with an air inlet, means for introducing the oily mist laden air from the crank case into said channel, and a conduit connecting said channel with the air inlet of the engine carbureter. 35

3. A lubricating system for rotary valves of internal combustion engines, comprising means for introducing into the air inlet of the engine carbureter preheated air carrying finely divided oil particles and means 40 for regulating the temperature of said preheated air comprising a water-jacketed conduit wall through which the preheated air is conducted.

In testimony whereof I affix my signature. 45
CLARENCE P. HOLLISTER.
